Electric Locomotive, all of which are of the type driven by electrical power delivered to the motor of such locomotive through the rails upon which it runs.

It is an object of my invention to provide means for greatly increasing the tractive effort which the locomotive can exert upon its load, or conversely increasing the acceleration of the locomotive and/or cars for a given amount of power consumed. It is a further object of my invention to provide such a means which will operate without in any way interfering with the delivery of electric power to the locomotive. Ancillary objects of my invention are to accomplish the above results at very low cost, and by means which can readily be applied with very little mechanical ability, and which do not require the use of tools.

These and other objects of my invention will best be understood by reference to the accompanying drawings, in which

Fig. 1 is a side elevational view of one form of electric locomotive to which my invention is applicable,

Fig. 2 is an enlarged elevation of one of the wheels of the locomotive of Fig. 1, with one form of a device according to my invention applied thereto,

Fig. 3 is a sectional view taken on the line 3—3 of Fig. 2,

Fig. 4 is a view similar to Fig. 3, but of a modified form of my invention,

Fig. 5 is an elevational view of a wheel equipped with a current conducting rim useful in connection with my invention, and

Fig. 6 is a sectional view taken on line 6—6 of Fig. 5.

Referring now to Fig. 1 of the drawings, numeral 10 designates generally a typical toy or model electric locomotive, provided with driving wheels 12 and 14 adapted to run upon one rail 16 of a track. It will be understood that the wheels 12 and 14 are duplicated upon the other side of the locomotive, and that such other wheels run upon a second rail 18 of the track, there being a third rail 20 intermediate rails 16 and 18, and adapted to act as one side of an electric circuit supplying current to the motor of locomotive 10, by means of the usual collector shoe (not shown). The return circuit is through the frame of the locomotive, wheels 12 and 14, and rail 16, a parallel return circuit usually existing through the wheels opposite to wheels 12 and 14, and rail 18, as is well known.

It is a commonly observed fact that locomotives

of this class, when running on one rail 16, do not have sufficient traction to pull a heavy load, and that the locomotive will slip or skid on the rail 16, especially when the locomotive is at a standstill or when it is pulling a heavy load, such as a long train of cars, uphill or on an oily track. This is usually noticed when full power is thrown onto the locomotive when it is at a standstill, or when the locomotive is being used to pull a heavy load, such as a long train of cars, uphill or on an oily track. While increasing the mass of the locomotive, as by weighting, would reduce the slippage on heavy pulls, such increase in mass concomitantly reduces the rate of the acceleration which can be achieved, besides almost always requiring additions to the locomotive profile which upset the lifelike appearance which such devices are intended to possess.

I have found that the desired increase in tractive effect of such locomotives can be obtained by taking steps to increase the coefficient of friction between certain of the driving wheels and the rails of the track. To this end, I apply to one (or at any rate, less than all) of the pairs of driving wheels a band or tire of a suitable material which has a much higher coefficient of friction, relative to the track, than does the metal of which the wheels are normally made. In Figs. 2 and 3, I have shown this tire as a ring of soft rubber or similar material 30, the same being applied around and seated in a groove 24 in wheel 12, and abutting the usual flange 22 of such wheel. Ring or tire 30 is preferably somewhat smaller in inside diameter than the diameter of groove 24, so that it must be stretched around the wheel. The tension in tire 30 resulting from such stretching produces a firm grip upon wheel 12, and insures that there will be no slippage of the tire in the groove 24, besides preventing the tire from working its way off the wheel during use.

It will have been noted from Fig. 1 that a tire 30 is applied to wheel 12 but not to wheel 14 of locomotive 10, the reason for this being that all the suitable materials for tire 30, such as soft rubber, Vinylite, synthetic rubber and the like, are good electrical insulators, and the use of such tires on all the wheels of the locomotive would effectively insulate the same from rails 16 and 18 of the track. By using the tires only upon less than all of the wheels, for example wheel 12 and its mate at the opposite end of the axle, I obtain the desired increase in friction without interfering with the operation of the locomotive. Where the locomotive incorporates more than four wheels, I can, of course, apply the frictional

tires to more of the driving wheels while still maintaining the desired electrical contact.

In Fig. 4, I have illustrated a slightly modified form of my invention, the tire 30' comprising a portion 31, conically annular in shape, to fit about the wheel, and an integral lip 32 adapted to pass over and around the edge of the flange of the wheel. The tire may obviously be readily applied to any desired wheels without the use of any tools, merely by slipping lip 32 over the flange, the tire being sufficiently stretchable to enable this to be done by the fingers. Since this form of the invention requires no special groove in the wheel, it is particularly applicable to existing locomotives.

I preferably form my novel tires by molding in one piece, but they may obviously be made by other methods, for example by connecting together narrow strips of the material. Therefore, I do not wish to be restricted to any particular method of fabrication of the devices.

The device shown in Fig. 4 accomplishes the desired results very well when applied to a locomotive in which less than all of the wheels are positively driven by the prime mover or motor. However, it is quite common for four-wheeled toy locomotives to have all the four wheels positively driven. In such a case, those wheels, provided with the tires 30', are effectively of larger diameter than the wheels which do not have tires, resulting in undesirable slipping of the latter and consequently wear and waste of power.

In Figs. 5 and 6 I have shown means for overcoming the above disadvantage, comprising a metallic auxiliary tire 40, which fits around these driven wheels, such as 14 of Fig. 1, which are not provided with the friction tires 30'. The body thickness of metallic tires 40 is such as to equalize the effective diameters of the driven wheels, or for that matter, of idler wheels of the locomotive. Tire 40 may be provided with integral bendable lugs or tabs such as 42, adapted to be bent over the flange of wheel 14 to secure the tire thereon, although such tabs may alternatively be provided so as to engage under the rim of spoked wheels if desired.

The combination of a pair of friction tires 30' and one or more pairs of metallic, conducting tires 40 enables an existing toy or model locomotive to be provided with the advantages of my invention without any actual structural changes being made, and at a very low cost. In the case of a new locomotive, it is of course more eco-

nomical to utilize the form of the invention shown in Figs. 2 and 3, the tires 30 being incorporated as a production matter, and the necessary equality of wheel diameters being designed into the equipment.

Having pointed out my invention in accordance with the statutes, and the preferred manner of its employment, I desire it to be understood that the above description is exemplary only, and that I do not intend to be restricted to the particular details of construction and application disclosed herein, except as required by the scope of the appended claim.

I claim:

- 15 In a toy electric locomotive having a plurality of flanged driving wheels adapted to drive said locomotive along a track and to make electrical contact with said track, the combination with certain of said wheels of a plurality of tires respectively carried thereby and each composed of a single piece of a resilient, rubber-like material having a high coefficient of friction with reference to metal, each of said tires being in the form of a narrow frustum of a thin-walled right 20 cone, with integral lip means extending from one edge of said frustum and curved back upon itself to engage resiliently over the flange of a driving wheel, and a second plurality of tires each composed of a single piece of metallic material, each of the last-named tires being also in the form of a narrow frustum of a thin-walled cone, provided with integral extensions passing about the flanged portion of a respective one of the remaining driving wheels, the radial thickness of all of said tires being substantially equal.
